WHOLE No. 31,777.

Iron Masts, Steeples, &c.

E. S. BOYNTON, OF ALEXANDRIA, V.A.

Letters Patent No. 773, dated March 26, 1861.

SPECIFICATION.

TO ALL WHOM IT MAY CONCERN:

Be it known, that I, E. S. BOYNTON, of Alexandria, Virginia, have invented certain new and useful improvements in the construction of Iron Masts and Spars for ships or vessels, and such other structures as require height and strength with comparatively small bases, and that the following is a full and accurate description thereof, reference being had to the accompanying drawings.

My invention consists in using for the desired structure flat bars of wrought iron or steel, made continuous in length from bottom to top, by riveting the ends of bars together, and winding them spirally from bottom to top, one-half the number of bars winding spirally in one direction, and the remaining half winding spirally around in the opposite direction.

Where the bars cross each other they are riveted securely together, and thus it is diagonally braced from bottom to top, presenting as stiff a structure as may be desired, braced in every direction, and stronger and steadier than any structure of equal size and height can be built with the same quantity of material.

Fig. 1st represents a section of a ship's mast, which shows fully the principle of this invention.

The use of flat bars of iron or steel extending from bottom to top of the structure, crossing each other diagonally and riveted firmly together at the points of crossing, without the aid of any longitudinal ribs, or circular ribs for support, constitutes the principal feature of this invention; the structure depending for its strength on the continuous spiral or diagonal braces formed by the flat bars.

It is this particular feature which distinguishes it broadly from many structures which would at first view appear to be similar in construction. For instance,

Boynton's Improvement in Iron Masts, Steeples, &c.

nothing is more common than lattice bridges and roofs of houses supported by lattice braces. So also have tubular bridges been constructed of continuous plates riveted together, and the Patent Office shows a tubular bridge with spiral braces crossing each other; but these, as well as all other structures known to me, differ from my invention in this, that, where the open lattice brace is used, it is always supported by longitudinal ribs, or beams, or circular ribs, or by frame work within the structure, to aid the lattice brace; besides, in all these cases the structure lies horizontally, and is supported at the ends.

My invention is for the construction of perpendicular structures with comparatively small bases, where the great object is to get height and strength with the least practicable weight. The great advantage of this mode of structure, as applicable to ship's masts, is apparent from the fact that it will reduce the weight of the timber masts now used about two-thirds, giving to an iron mast constructed as herein shown, the advantage of being really cheaper, and only about one-third the weight of the timber masts in common use, yet at the same time stronger. The calculation of weight here referred to is made in comparison with the mast of a frigate. Having determined the width and thickness of the iron bars to be used in the construction of a mast, which depends on the size and height of the mast to be made, I cause the iron bars to be drawn between dies, to give them the desired spiral curve where they are too stiff to be readily bent, and then punched at the required points of intersection, which is a matter of mere calculation after the size and form of the structure have been determined on. In commencing, the bars should be of unequal lengths, commencing with the base to which they are secured, so that the joining of the ends of the bars will not be in the same horizontal plane, for if they were, the strength of the structure would depend on the rivets or bolts which secure the ends of the bars together, instead of the bars themselves. But, by breaking the joints, the strength is greatly increased. Where great height and strength are required, the bars of iron should be both wider and thicker at the base than at the top, gradually decreasing from bottom to top. If the structure is in form of a cone, and the top greatly smaller than the base, the bars must so decrease in size as to admit room for riveting them together at the smaller end, or some few of the bars may be stopped short of the top, taking care to continue a sufficient number to the top to give the required strength.

The mode of stepping the mast will readily occur to any mechanic. In place of building the mast, and then putting it in place, where large structures are to be used, as in large ships, the bars being punched and prepared, and a circular wooden frame on which to begin it, the structure may be as readily put together as any ordinary framing, and by means of a small portable forge the riveting may be expedited, and the mast built in the ship. As the structure progresses, it affords the best means of scaffolding, and thus may the whole mast be built, or only so much as generally constitutes the main mast, and the remainder or top mast be constructed below and hoisted in place, taking care that the ends of the two parts should be so united as to make the bars continuous and of equal strength with

Boynton's Improvement in Iron Masts, Steeples, &c.

the remainder of the work. The size of the masts in large ships causes them to occupy much room, so that, when constructed as above, the lower portions may be made water-tight, and readily be converted into water tanks, and the water conveyed by pipes to different parts of the ship, or they may be fitted up as receptacles for various things, and thus economize space. The necessary fixtures for securing the masts in place and fixing the sails and rigging may be as readily attached to them as to timber masts, and the mode of doing it will suggest itself to the builder. I have suggested the use of flat bars of iron, but it is apparent that for the upper part of the mast, or top mast or any portion of it, flat bars of steel may be substituted for the flat bars of iron, and the mast be made still lighter and more elastic, and so may bolts with nuts be substituted for rivets without departing from the spirit of this invention. It is sometimes necessary to cut away masts; if constructed as above, they would be less top-heavy than the timber masts, and, therefore, the necessity would be less; but it is practicable to substitute bolts for rivets in a section of the mast, so that by unscrewing them the ends of the bars would all be separated, and the mast would fall.

The mast here described suggests at once that upon the same principle many other structures requiring height, stiffness, and as little weight as practicable, may be built cheaper and yet more lasting than similar structures ever were built, and even more beautiful.

This principle of continuous flat bars, secured by diagonal or spiral braces applied to perpendicular structures, renders unnecessary the use of columns for sustaining the weight, and introduces many improvements in the construction of high and lofty structures. On this principle cheap and permanent light-houses may be built, and readily made higher and constructed more quickly than on any other plan. Such portions of it as would be necessary for the protection of the light-house keeper and the lamps might be readily inclosed.

By this plan also spires or steeples for churches of any required height may be readily erected, more speedily, much cheaper, far higher, and more durable, than by any other mode of structure hitherto known. This mode of structure permits all the work to be done from the inside if desired; the work itself affording the readiest means of scaffolding as it progresses. The iron bars all being punched to receive the rivets, they could be put through from the outside and readily secured, and the work progress with far greater safety to the workmen & less exposure than where scaffolding for similar structures is required to be on the outside; or if the structure be such as to require a stairway, as in towers and light-houses, then this may keep pace with the structure itself.

The structure being of iron, and the bars being at any required distance apart, and the whole structure well painted, it would present a beautiful appearance, without any covering, for the steeple of a church, as shown in fig. 2; or the whole may be readily covered in from the inside, if desired, by planks dressed to fit the outer circumference placed perpendicular and secured to the lattice frame. There

Boynton's Improvement in Iron Masts, Steeples, &c.

could be no reason for covering in the lattice work, unless as a mere question of taste as to its appearance.

This principle may also be applied to the construction of shot towers, chimneys for foundries and machine shops, and steamboat chimneys; the frame work, constructed as described, may be readily covered in with sheet iron or any suitable material, and the structure being secured at the base would be stable, and could not be blown down or broken off.

The circular form shown in the drawings is that deemed best adapted for strength, though on the same principle rectangular or many-sided structures may be built. But it is evident that the strength and weight of the structure, as well as its exact form, may be varied to suit the purpose for which it is required, without departing from the principle of its construction. In the erection of a structure like those designed, two or more wooden circles of the required diameter should be made, and to these the bars would be secured temporarily, to hold them in place until they are bolted or riveted, when the frames may be moved up as the work progresses, each frame being reduced to suit the diameter of the structure; or, by making a model of the structure on an exact scale of proportion, the distance apart of the rivet holes may be calculated with accuracy, and the iron all punched where made, and readily bent to suit the curvature of the circumference; when, after the structure was started, the bars would necessarily come into place without the aid of a frame, and where they are very light, they may, in crossing each other, be placed under and over, which will aid to hold them in place.

On this principle also telegraph or lamp posts may be made, relying in every instance on the continuous diagonal or spiral braces for their support, without any longitudinal or circular ribs or internal framing.

Having thus fully described my invention and the various uses to which it may be applied, what I claim is—

The constructing of masts and spars, and such perpendicular structures as require height and stability, by means of flat bars of wrought iron or steel made continuous by riveting the ends of the bars together, and winding them spirally around from the bottom to the top of the structure, one portion winding around in one direction and the other portion winding around in the reverse direction, so as to form spiral or diagonal braces throughout the structure, secured together at the points of intersection, and relying on said continuous braces for their support without the aid of longitudinal or circular ribs, or any internal framing, substantially as herein described.
